(57) **CLAIM**

The ornamental design for a hockey stick, as shown and described.

DESCRIPTION

FIG. 1 is a front, left perspective view of a right-handed hockey stick showing my new design;

FIG. 2 is a left side view thereof;

FIG. 3 is a right side view thereof;

FIG. 4 is a front view thereof;

FIG. 5 is a rear view thereof;

FIG. 6 is a bottom view thereof;

FIG. 7 is a top view thereof;

FIG. 8 is a cross-sectional view at 8-8 in FIG. 2 thereof;

FIG. 9 is a cross-sectional view at 9-9 in FIG. 2 thereof;

FIG. 10 is front, right perspective view of a left-handed hockey stick;

FIG. 11 is a right side view of FIG. 10;

FIG. 12 is a left side view of FIG. 10;

FIG. 13 is a front view of FIG. 10;

FIG. 14 is a rear view of FIG. 10;

FIG. 15 is a bottom view of FIG. 10;

FIG. 16 is a top view of FIG. 10;

FIG. 17 is a cross-sectional view at 18-18 in FIG. 11 thereof; and,

FIG. 18 is a cross-sectional view at 17-17 in FIG. 11 thereof.

1 Claim, 18 Drawing Sheets
